STRIP LABELER

Filed July 25, 1930

UNITED STATES PATENT OFFICE

WILLIAM M. MCNEIL, OF CHICAGO, ILLINOIS, AND BERNARD T. BALLARD, OF FORT DODGE, IOWA, ASSIGNEES TO UNITED STATES GYPSUM COMPANY, OF CHICAGO, ILLINOIS, A CORPORATION OF ILLINOIS

STRIP LABELER

Application filed July 25, 1930. Serial No. 470,575.

This invention relates to an apparatus for applying labels in continuous strip form to articles such as strips of plaster board and has reference more particularly to an apparatus of the class described for applying the adhesive to the strip label, and then applying the strip label to the sheet of material to be labeled.

In the manufacture of certain classes of merchandise, such as plaster board, or other composition boards, it is customary to apply a continuous strip label to the board as it is manufactured, this label containing sales indicia, such as trademarks, patent numbers, etc. It is important that a machine of this character should apply the adhesive uniformly, so that good bond is obtained between the strip label and the sheet of material. It is also important that a continuous supply of the sheet labels be maintained, so that unlabeled boards will not be produced.

An object of this invention, therefore, is to provide an apparatus for applying a continuous strip of labeling material to boards or other sheets which are manufactured in continuous strips.

Another object of the invention is to secure the uniform application of adhesive to the labeling strip.

A further object of the invention is to provide an apparatus of the class described, in which a continuous supply of the strip label is assured at all times; also to improve strip labeling apparatus in other respects herein-after specified and claimed.

Reference is to be had to the accompanying drawing forming a part of this specification, in which

Fig. 1 is a sectional elevation of the strip labeling apparatus,

Fig. 2 is a plan view of the apparatus,

Fig. 3 is a sectional elevation of the holder for rolls of the strip labels, used on either type of apparatus, taken on line 3—3 of Fig. 1.

The article to be labeled may consist of a plaster board 10, or other material in sheet form, which passes continuously along a table 11. The strip label 12 bearing the desired advertising indicia is supplied in the

form of form rolls 13 which are mounted on reel shafts 14. The reel shafts 14 are preferably two or more in number, and are rigidly secured, one on each end of a pivotally mounted beam 15, which is rotatably secured on a central shaft 16, the latter being rotatably mounted in a bearing bracket 17 secured to the framework 18 of the machine. A roll guide 19 is rigidly secured to the shaft 14 adjacent the beam 15, by a set bolt 20. Outstanding arms 21 are formed on the roll guide 19 for the purpose of preventing the roll of strip labeling material 13 from telescoping. A second roll guide 22 is rotatably mounted upon the shaft 14 and is provided with outstanding arms 23 for supporting the roll 13. The roll guide 22 is quickly detachable from the shaft 14. The shaft 14 is provided with a slot 25 into which is pivotally mounted by means of pins 26, a pair of catch arms 27 which are normally urged to spread apart by means of a coil spring 28. Catch shoulders 29 are formed on the outer ends of catch arms 27, these catch shoulders being adapted to engage the outer surface of the roll guide 22, after said roll guide has been slipped over tapered surfaces 30 formed on the outer ends of the catch arms 27. A pin 26a limits the spreading movement of the catch arms 27 under the action of spring 28.

It will be noted that one roll may be quickly substituted for a roll which has become exhausted, and also the position of the roll being used is accurately controlled by means of a catch shoulder 31 formed on the central portion of beam 15, which engages a similarly shaped notch formed in the bearing bracket 17. The shaft 16 extends beyond the bearing bracket 17, and is provided at its outer end with a collar 32 which serves to confine a coil spring 33 between said collar and the bracket 17, so that the catch shoulder 31 is normally urged into locking position in its notch, thus maintaining the beam 15 in substantially horizontal position. When a roll of the strip label become exhausted, the operator quickly disengages the beam lock shoulder 31 from its notch by pulling the beam 15 outwardly against the action of spring 33, and then

swinging it around until the new roll of label strip is in position for use on the machine.

As the strip label 12 unrolls from the roll 13, it passes under an idler roll 35, which is 5 rotatably mounted upon a shaft 36 being prevented from axial movement by fixed collars 36a. One end of the shaft 36 is pivotally supported in a bracket 37, and the other end of said shaft is received in a saddle bracket 38 so that the roll 35 and shaft 36 may be easily 10 swung upwardly to permit rapid threading of the strip label through the machine.

After passing the roll 35, the strip label 12 passes upwardly over an adhesive applying 15 roll 38 which is rotatably supported, being secured to a shaft 39 which is rotatably supported in bearings 40 formed on the outer edges of an adhesive pan 41 into which the roll 38 dips. Adhesive is supplied to the pan 20 41 by a closed reservoir 42 which is supported on suitable framework 43. A flexible tube 44 leads from the closed container 42 down into the pan 41 the lower end of said tube being secured in a suitable socket 45 formed in said pan 25 by means of a set screw 46. The lower end of the tube 44 is thus positioned at substantially the liquid level desired in the pan 41, and as soon as the level falls below the bottom of said tube, more adhesive liquid from the 30 reservoir 42 runs into said pan. A scraper 47 extends transversely over the top of pan 41, being adjustably secured thereto by set screws 48 and 49 so that the inner edge of said scraper bears against the periphery of the roll 38 and thus prevents an excess of adhesive 35 from being applied to the surface of labeling strip 12.

The shaft 38 extends outwardly beyond one of the bearings 40 and is provided on its outer 40 end with a pulley 50 connected by a belt 51 to a pulley 52 which is secured to the outer end of a drive shaft 53. The shaft 53 is rotatably supported in bearings 54 secured to framework 55 of the machine, and a pressing wheel 56 is secured to said shaft 53, being 45 adapted to press the labeling strip 12 downwardly onto the face of the moving sheet of material 10. The belt 51 thus causes the positive rotation of the adhesive roll 38 in unison with the rotation of pressing roll 56. The framework 18 is preferably composed of a pair of angle bars spaced apart and formed into a U shaped section 58 at one end. This section 58 is provided with a pivot bracket 59, which in turn is pivotally secured by a bolt 60 to a horizontal channel bar 61 rigidly supported by framework not shown. The opposite end of framework 18 is suspended from a fixed bar 62 by means of eye bolt 63 and turnbuckle 64. Pivot brackets 65 are secured to the outer ends of frame members 18 and a transverse pivot pin 66 is supported in said basket 65. Framework 55 supporting the bearing brackets 54 is pivotally supported 50 upon pivot pin 66 at its inner end. A red

67 is pivotally secured to the outer end of framework 55, said rod extending vertically and having secured to its lower end, a brush 68 which bears against the labeling strip 12 after application to the plaster board 10, so as to cause said strip to adhere firmly to said plaster board. 70

In order to sound an alarm when a roll 13 of the label strip has been exhausted, we provide a metal roller 70 which is rotatably supported upon a lever 71, said roller 70 being normally urged into contact with the metal idler roll 35. The lever 71 is pivotally supported upon a pivot pin 72, and the outer end of said lever is provided with a counterweight 73 serving to urge the roller 70 in a clockwise direction, as seen in Fig. 1. The clockwise movement of lever 72 is limited by a stop 74. An electrical connecting wire 75 is connected to the lever 71, said wire leading in series 80 through an alarm device such as a bell 76, and batteries 77, and then is grounded to framework 18 by electrical wire 78. Thus when the roller 70 contacts with roller 35 after the roll of strip label has been exhausted, the bell 76 is actuated by the passage of current from the batteries 77, thus signalling the operator who then swings the beam 15 about to bring a new roll of strip label into operating position. 85

In operation, the label strip 12 unwinds from roll 13, which is rotatably supported upon shaft 14 and prevented from telescoping by arms 21 and 23. The strip passes under idler roll 35 over electrical contact roll 70 and up over the adhesive roll 38 which dips into the adhesive pan 41 supplied with adhesive from reservoir 42 by tube 44. The label strip then passes downwardly around pressing wheel 56 which presses the strip onto the top surface of plaster board 10, or other sheet-like materials, brush 68 also serving to firmly attach the label strip to the plaster board. When the roll 13 is completely unwound from the shaft 14, roller 70 contacts with roller 35 and closes the circuit which includes the electric alarm bell 76, thus indicating to the operator that a new roll of label strip must be supplied. This new roll is put into operative position by pulling beam 15 outwardly along shaft 16 against the action of spring 33, until the locking shoulder 31 is disconnected from its slot, and then rotating the beam 15 through half a revolution until the new roll of label strip is in position. The shaft 36 is then swung upwardly about its pivot bracket 37, and the new label strip 12 is led over roller 38 and down under roller 56 onto the top surface of the plaster board 10. The shaft 36 is then lowered to its horizontal position so that the strip 12 passes between rolls 35 and 70. 100

We would state in conclusion that while the illustrated examples constitute a practical embodiment of our invention, we do not wish to limit ourselves to these details, since 105 110 115 120 125 130

manifestly, the same may be considerably varied without departing from the spirit of the invention as defined in the appended claims.

5 Having thus described our invention, we claim as new and desire to secure by Letters Patent:

1. In a label strip applying apparatus, a pivotally mounted roll supporting element 10 having a plurality of label strip rolls rotatably mounted thereon, means for anchoring said element in a plurality of positions so that full rolls of label strip may be successively brought into operative position, 15 means for applying adhesive to one face of said label strip, and means for pressing said label strip onto a moving sheet of material.

2. In a label strip applying apparatus, a pivotally mounted supporting frame having 20 a roll of label strip rotatably supported thereon, means for applying adhesive to one face of said label strip, and means associated with said frame member adapted to press said label strip onto a moving sheet of material.

3. In a label strip applying apparatus, a supporting framework, a pivotally mounted beam on said framework, a pair of roll supporting shafts on said beam, roll supporting 30 arms associated with each of said shafts, means for maintaining said beam in a plurality of positions so that full rolls of label strip can be successively brought into operative position, means for applying adhesive 35 to one face of said label strip, and means for applying said label strip to a moving strip of material.

4. In a label strip applying apparatus, a pivotally mounted supporting frame, a pressing 40 roll rotatably mounted on said frame and adapted to roll on a moving strip of material, means for supplying a label strip to be pressed against said material strip by said roll, means for supplying adhesive to said 45 label strip, and adjustable means for changing the height of said frame and roll.

5. In a label strip applying apparatus, a supporting frame, a pressing roll adapted to be driven by friction contact with a moving 50 strip of material, an adhesive roll driven by said pressing roll, and means for causing a label strip to press continuously over said adhesive roll and under said pressing roll to be applied to said strip of material.
